A. B. THOMPSON, OF OWEGO, NEW YORK.

Letters Patent No. 87,124, dated February 23, 1869.

IMPROVED RAILWAY-FROG.

The Schedule referred to in these Letters Patent and making part of the same.

To all whom it may concern:

Be it known that I, A. B. THOMPSON, in the town of Owego, county of Tioga, and State of New York, have invented a new and improved Frog for Railway-Tracks; and I do hereby declare that the following is a full and exact description thereof, reference being had to the accompanying drawings, and to the letters of reference marked thereon.

In the accompanying drawings—

Figure 1 shows the top of the frog.

In Figure 2 the frog is inverted, and a thin plate removed, to show the moving-parts.

Figure 3 is a vertical longitudinal section through the line D D, figs. 1 and 2.

The principal part or body of the frog is shown at A, fig. 1, with four elevations thereon, forming the tracks diverging from the centre. In the centre itself is a circular opening, in which is a disk or plate, with a single section of track raised thereon. This disk rotates like a turn-table, to bring the rail upon it in connection with the track on which a train is approaching.

In the fixed tracks, on the ends of the frog, are slots, (see fig. 1,) in which are pivoted suitable-shaped tappets, d d d d, which descend and terminate in points near the bottom of the frog.

Inside, and near the bottom, are two disks, C C, figs. 2 and 3, which partially rotate as they are actuated by the tappets, pivoted in the rails above, the lower points of the tappets entering holes near their periphery.

Each of these disks is also provided with a projection pointing toward the centre and each other, and entering open spaces in the sides of a plate directly under the turn-table, and firmly attached to and moving with it. (See fig. 2.)

These several parts are so arranged, that when the rail on the turn-table is in position for cars to pass over, the tappets in the rails on which cars are approaching, are down level with the surface of the rails, while the tappets in the other two rails are elevated above them, in the form of inclines, facing outward. But if the shifting-rail is wrong, the first wheel that comes upon the frog strikes the tappet on that side, and presses it down, the point of the tappet in the disk

O turns it, while the projection on the disk engages in the plate on the bottom of the turn-table, thus turning it, with its rail, directly in line with the rail whose tappet has been struck by the wheel of the coming train.

As the disks C are turned by tappets in one line of rails, of course the opposite sides of the disks, turning in an opposite direction, raise the tappets on that side above the rails, ready to be struck, and bring the turn-table back when a train must pass on that track.

By reference to fig. 2, it will be seen that the projections on the disks C C, and the plate in which they operate, are so constructed that the rail is securely locked in position, and any power applied to the turn-table cannot move it unless the disks C C are turned, which can only be done by means of the tappets d.

In figs. 2 and 3 will be seen a flat plate or bar, c, the centre of which is directly beneath the centre of the turn-table, and held by a pin. In the ends of this bar are slots, in which small pins work freely, the pins being fast in the projections on the disks C. When a tappet is struck by a wheel, it turns the disk on that end only, but the pin in that disk swings the bar on its centre, the other end of the bar unlocks the disk it is attached to, moving it round, and both disks are thereby operated at the same time.

What I claim as my invention, and desire to secure by Letters Patent, is—

1. The combination of the turning-disk B, bearing the shifting section of rail, and provided with the locking-notches underneath, and the operating-disks C C, with their locking-projections, working in the notches of the disk B, substantially as herein specified, all being enclosed in a frog-case, A, which limits their movements, and protects them from disarrangement.

2. The combination of the tappets d d d d, disks C C, when constructed and arranged to automatically adjust and lock a movable section of rail in a railway-frog, substantially in the manner herein described.

A. B. THOMPSON.
